Patented June 7, 1904.

UNITED STATES PATENT OFFICE.

STARLING ROREX, OF WATONGA, OKLAHOMA TERRITORY.

DESIGN FOR A BADGE.

SPECIFICATION forming part of Design No. 36,944, dated June 7, 1904.

Application filed May 2, 1904. Serial No. 206,075. Term of patent 3½ years.

To all whom it may concern:

Be it known that I, STARLING ROREX, a citizen of the United States, residing at Watonga, in the county of Blaine and Territory of Oklahoma, have invented a new, original, and ornamental Design for Badges, of which the following is a specification.

The figure is a plan view of a badge, showing my new design.

What I claim as new, and desire to secure to by Letters Patent, is—

The ornamental design for a badge, as shown.

STARLING ROREX.

Witnesses:

JOHN ROREX,
ELER ROREX.
